UNITED STATES PATENT OFFICE.

WILLIAM C. HISLOP, OF DETROIT, MICHIGAN.

ASH RECEPTACLE.

Application filed April 25, 1925. Serial No. 25,805.

To all whom it may concern:

Be it known that I, WILLIAM C. HISLOP, a citizen of the United States, and residing at Detroit, in the county of Wayne and State 5 of Michigan, have invented a new and Improved Ash Receptacle, of which the following is a specification.

This invention relates to ash receptacles and the object of the invention is to provide 10 an ash receptacle mounted on wheels and arranged so that it may be easily dumped.

Another object of the invention is to provide an ash receptacle which may be taken up a flight of stairs, the said receptacle 15 being provided with a safety device arranged to engage the steps as it is being taken up a flight of stairs.

Another object of the invention is to provide an ash receptacle supported on wheels 20 and provided with means for normally supporting the receptacle in the upright position.

A further object of the invention is to provide an ash receptacle having a safety 25 device which is engaged by the receptacle upon movement of the receptacle to the dumping position and upon subsequent movement of the receptacle to the upright position the safety device is moved out of 30 operative position.

These objects and the several novel features of the invention are hereinafter more fully described and claimed and the preferred form of construction by which these 35 objects are attained is shown in the accompanying drawings in which—

Fig. 1 is a perspective view of an ash receptacle embodying my invention.

Fig. 2 is a side elevation thereof.

Fig. 3 is a front elevation of the lower portion of the ash receptacle.

Fig. 4 is a perspective view of the mechanism for holding the receptacle in the upright position.

Fig. 5 is a perspective view of the latch.

Fig. 6 is a perspective view of one of the safety dogs.

As shown in Figs. 1 and 3 a shaft 1 is provided on which the wheels 2 are rotatably 50 mounted. Secured to the shaft 1 are two members 3 to which the frame members 4 are secured, the frame members 4 being return bent at the upper ends to form a handhold. Also secured in the members 3 are the 55 two supporting legs 5 which support the frame in the upright position, the said mem-

bers 5 being provided with downwardly bent ends 6 for this purpose. A frame member 7 connects the members 4 at the upper end and a frame member 8 connects the members 4 intermediate the ends. A receptacle 9 is provided having brackets 10 fitting over the frame member 8, the arrangement being such that the receptacle 9 may be turned on the frame member 8. To hold the receptacle 9 60 in the upright position a latch bar 11 is provided as shown in Fig. 5 having an aperture 12 therethrough by which the latch bar may be pivoted to the receptacle and the latch bar is provided with a catch 13 adapted to engage over the edge of the receptacle 9 and the frame member 7 as shown in Fig. 4. The latch bar 11 is provided with a handle 14 at the end by means of which the latch bar may be turned on its pivot. A pair of dogs 70 15 are pivotally mounted on the cross frame member 8 and each dog is provided with a lug 16 to limit movement of the dog 15 in one direction by engaging the respective frame member 4. As shown in Fig. 6 each 75 dog 15 is provided with an enlarged body portion 19 so that the dog 15 normally hangs in the position shown in Fig. 2 by gravity. Each dog 15 is provided with an arm 20 having a slot 21 and an adjustable arm 22 is provided having a slot similar to the slot 21 80 through which a bolt 23 extends. The arm 22 is provided with a lug 24 extending through the slot 21 and the arm 20 is provided with a lug 25 extending through the slot 21, the two lugs 24 and 25 forming 85 guides for the arms and providing an arrangement so that when the bolt 23 is tightened the arm 22 is firmly secured to the arm 20.

In operation after the receptacle 9 has been filled, the user, by grasping the handles 17 tips the entire device back on the wheels 2 so as to raise the lugs 5 and ends 6 off the floor. While in this position the device may 100 be drawn up a flight of stairs and the dogs 15 which are loosely pivoted on the frame member 8 allow the arms 22 to engage the steps as the device is drawn up the stairs so that the device may be rested on each step as it is drawn up without danger of slipping. This device may be also used on a spiral staircase as one of the arms 22 of the dog 15 105 will always engage the steps.

To dump the receptacle it is only necessary 110 to raise the latch member 11 until the portion 13 is disengaged from the frame mem-

ber 7 at which time the receptacle 9 may be turned on its pivot to the dumping position shown in Fig. 2. As will be noted from Figs. 1, 2 and 3 a flat spring metal bracket 18 is provided on each side of the receptacle and as the receptacle 9 is turned to dumping position the spring metal brackets 18 are moved past the dogs 15. After the receptacle has been dumped it may be turned back to the upright position shown in Fig. 1 and the brackets 18 which contact the dogs 15 move the dogs 15 to the position shown in full lines in Fig. 1 at which time it is possible to wheel the device down a flight of stairs without the dogs catching on the steps. By this arrangement the ash receptacle may be kept in the basement and when the ash receptacle is filled, by pressing down on the lugs 16 the dogs 15 may be moved out of engagement with the brackets 18 to the position shown in dotted lines in Fig. 1 whereupon the device may be drawn up the basement stairs with the arms 22 of the dogs 15 acting to prevent the device from slipping and after the device has been taken out to the alley and dumped it may be returned to the position in Fig. 1 and the lug 13 again engaged over the frame member 7 at which time the dogs are held out of position to engage the steps and the device may be wheeled down the stairs without difficulty as the device is light and easy to handle when the receptacle is empty. While I have described this device for use with ashes it will be readily understood that it may be used for rubbish, fruit, vegetables or other material to be conveyed.

From the foregoing description it becomes evident that the device is very simple and efficient in operation, will not easily get out of order, is composed of few parts and is of consequent low manufacturing cost and provides a device which accomplishes the objects described.

Having thus fully described my invention, its utility and mode of operation, what I claim and desire to secure by Letters Patent of the United States is—

1. An ash receptacle comprising a frame, a pair of wheels mounted on the lower end of the frame, a pair of legs supporting the frame in upright position on the wheels, the frame being provided with lower and upper cross members, a receptacle pivotally mounted on the lower cross member, a latch on the receptacle adapted to be engaged over the upper cross member to hold the receptacle in upright position, a pair of dogs pivotally

mounted on the lower cross member and normally extending from the sides of the frame, means for limiting the turning of the dogs on their pivots and a spring metal bracket on each side of the receptacle adapted to engage the dogs by movement of the receptacle to the dumping position, the said spring metal brackets moving the dogs out of operative position upon subsequent movement of the receptacle to the upright position. 60

2. An ash receptacle comprising a frame, a pair of wheels on which the frame is mounted, a pair of legs extending from the frame and adapted to support the frame in a vertical position, a receptacle pivotally mounted on the frame and adapted to be turned on its pivot within the frame, a pair of dogs normally extending from the side of the frame and pivotally mounted on the frame, means on the receptacle whereby the dogs are moved out of position upon turning of the receptacle from dumping position to upright position, and means for securing the receptacle in the upright position. 70

3. An ash receptacle comprising a wheel supported frame having cross members, a pair of legs connected to the frame for supporting the frame in vertical position, a receptacle pivotally mounted on one of the cross members of the frame, a pair of dogs pivotally mounted on the frame and extending from the sides thereof and adapted to engage the steps when the device is drawn up a flight of stairs, and means on the receptacle for moving the dogs out of operative position upon turning of the receptacle to upright position after it has been dumped. 85

4. An ash receptacle comprising a framework, a receptacle pivotally mounted on the frame-work, a pair of wheels rotatably mounted on the lower end of the frame-work and supporting the frame-work, a pair of dogs pivotally mounted on the frame-work and normally extending therefrom, the frame-work being provided with a pair of hand holds at the upper end, a latch for holding the receptacle in the upright position, and a spring metal bracket on each side of the receptacle adapted to engage the dogs upon movement of the receptacle to the dumping position, the arrangement being such that upon subsequent movement of the receptacle to the upright position the dogs are moved out of operative position. 100

In testimony whereof I sign this specification.

WILLIAM C. HISLOP.
